FLUID FLOW SENSOR

Anthony D. Lambo and Rodney W. Reder, Waterbury, Conn., assignors to North American Philips Corporation, New York, N.Y.

Filed Apr. 24, 1970, Ser. No. 22,621

Term of patent 14 years

Int. Cl. D24—02

U.S. Cl. D83—1

FIG. 1 is a perspective view of a sensor which illustrates the new design;

FIG. 2 is a top plan view of the sensor shown in FIG. 1;

FIG. 3 is a front elevational view of the sensor shown in FIG. 1;

FIG. 4 is a bottom plan view of the sensor shown in FIG. 1;

FIG. 5 is a rear elevational view of the sensor shown in FIG. 1;

FIG. 6 is a left side elevational view of the sensor shown in FIG. 1; and

FIG. 7 is a right side elevational view of the sensor shown in FIG. 1.

The broken lines represent only a partial environment for a sensor, and are shown merely for illustrative purposes.

We claim:

The ornamental design for a fluid flow sensor, as shown and described.
